UNITED STATES PATENT OFFICE.

ELWOOD C. PHILLIPS, OF CHICAGO, ILLINOIS, ASSIGNOR OF ONE-HALF TO CHARLES F. GABRIEL, OF CHICAGO, ILLINOIS.

BUNG-HOLE CLOSURE FOR BARRELS AND THE LIKE.

1,173,606.

Specification of Letters Patent.

Patented Feb. 29, 1916.

Application filed December 12, 1914. Serial No. 876,785.

To all whom it may concern:

Be it known that I, ELWOOD C. PHILLIPS, a citizen of the United States, residing at Rogers Park, Chicago, in the county of Cook and State of Illinois, have invented certain new and useful Improvements in Bung-Hole Closures for Barrels and the like, of which the following is a specification.

This invention relates to improvements in bung hole closures for barrels and the like and one of the objects of the same is to provide an improved closure of this character, which may be quickly and readily adjusted to open or close the bung hole.

15 A further object is to provide means for holding the bung in position adjacent the bung hole within the container and against displacement or loss and for maintaining the bung in alinement with the bung hole.

20 To the attainment of these ends and the accomplishment of other new and useful objects as will appear, the invention consists in the features of novelty in substantially the construction, combination and arrangement of the several parts, hereinafter more fully described and claimed and shown in the accompanying drawing illustrating the invention and in which—

Figure 1 is an elevation of a barrel having 30 a bung hole closure applied thereto, constructed in accordance with the principles of this invention. Fig. 2 is a sectional view taken on line 2—2 Fig. 3 and showing two bung hole closures, one adapted to close the 35 bung hole in the side and the other to close the opening in the end of the barrel. Fig. 3 is a sectional view taken on line 3—3, Fig. 2. Fig. 4 is a detail view of the bung closure. Fig. 5 is a detail view of the anchor 40 or support for a bung adapted to close an opening in the side of the barrel. Fig. 6 is a similar view of an anchor or support for a bung in the end of the barrel. Fig. 7 is a detail view of a tool or implement for 45 manipulating the bung.

In the drawing the closure is shown as being adapted for use in connection with barrels, but it is to be understood that it may be adapted for use with any suitable 50 container.

Referring more particularly to the drawing, the numeral 10 designates a barrel having a bung hole in the side thereof and fixedly arranged within this bung hole is 55 a collar 11 having a threaded opening 12,

and this collar is secured in position in any desired or suitable manner.

Secured within the barrel and at any suitable position adjacent the bung hole is an anchor or support 13 which may be held in 60 position in any suitable manner and is provided with a portion 14, having a threaded opening 15 and this threaded opening 15 is arranged in alinement with the threaded opening 12 of the collar 11. 65

A bung 16 is provided for closing the bung hole and this bung is preferably constructed with an enlarged portion 17 intermediate its ends, preferably arranged in closer proximity to one end of the bung 70 than the other end. The portions 18, 19 of the bung, on opposite sides of the enlarged portion 17 are preferably of the same size and are each screw threaded, the portion 19 being adapted to enter in the bushing 14 to 75 engage the threads therein, while the portion 18 of the bung is adapted to enter the screw threaded opening 12 in the collar 11.

The portion of the bung 19 on one side 80 of the enlarged portion 17, and which engages the bushing 14 is of such a length that when the bung is adjusted to cause the threaded portion 18 to enter the threaded opening 12 of the collar 11, and the face 20 to engage the inner face of the collar 11, it 85 will still remain in engagement with the bushing 14.

The anchor or support 13 is spaced from the wall of the barrel, or that portion thereof containing the collar or bung hole and the enlarged portion 17 of the bung is arranged between the anchor or support and the wall of the barrel so that this enlarged portion not only acts as a closure for the bung hole, but also serves as a means for 90 limiting the inward movement of the bung and to prevent its disengagement from the anchor or support. The anchor or support holds the extremity 18 of the bung in alinement with the threaded opening 12 of the 100 collar 11 and this end of the bung is preferably provided with a socket or seat 21 for the reception of a tool or implement 22. This implement 22 is passed through the bung hole, when the bung is unseated as 105 shown in Fig. 3, so that the extremity of the implement will engage the socket 21 of the bung, and by rotating the implement, the bung will also be rotated, and its threaded engagement with the anchor or support 110

13 will cause the bung to be fed toward the bung hole and the threaded extremity 18 therecf will enter the threaded opening in the collar 11. This adjustment of the 5 bung may be continued until the face 20 of the enlarged portion 17 engages the inner face of the collar and thereby tightly sealing or closing the bung.

When it is desired to open the bung hole, 10 the implement is connected with the bung and the bung rotated in the opposite direction which will not only cause the threaded end 18 to be disengaged from the bung hole, but will cause the bung to be fed away from 15 the bung hole by means of the threaded engagement of the portion 19 with the anchor or support 13.

In Figs. 2 and 3 there is shown a means whereby the bung may be employed for closing an opening in either the side or the end 20 of the barrel and when it is desired to close an opening in the end of the barrel, an anchor or support 23 may be employed and in this instance, one end of the anchor is secured as at 24 to the head of the barrel and the other end secured as at 25 to the side of the barrel. This anchor or support is provided with a bushing 26 similar to the bushing 14, and the same bung may be employed 30 in both instances.

With this improved construction it will be manifest that the bung will always be maintained in position and in alinement with the bung hole so that the bung hole may not 35 only be readily and quickly opened or closed, but the bung may be supported some distance from the bung hole to permit the contents of the container to pass out of the bung hole and at the same time the bung will be held 40 in true alinement with the bung hole, so that its proper engagement with the wall of the bung hole when the bung is adjusted to close the opening, will be assured, and by closing the bung hole from the inside of the 45 container, a more perfect seal may be obtained and there will be no protruding or projecting parts extending beyond the outer surface of the container. Furthermore, with this improved construction, the same 50 bung may be employed a number of times and the bung will always be in position for ready use. It will also be manifest that by the threaded engagement of the bung with the anchor or support the bung will be maintained in its adjusted position and will be held against floating movement within the 55 container.

What is claimed as new is:

1. The combination of a container having 60 an opening in the wall thereof, a closure for the opening, said closure disposed inside of the container, a support for the closure adjacent the opening and spaced from the wall of the container, means for manipulating 65 the closure, and interengaging means on

the wall of the opening and the portion of the closure which enters the opening to secure the parts together, the said means on the wall of the opening being fixed with respect to the wall of the container.

2. The combination of a container having a threaded opening in the wall thereof, a closure for the opening disposed within the container, a support for the closure and with which support the closure has adjustable engagement, a portion of the closure adapted to enter the said opening from the inside thereof, threads on said portion adapted to engage and disengage the threads in said opening, and means for manipulating the closure.

3. The combination of a container having a threaded opening in the wall thereof, a closure for the opening disposed within the container, a support for the closure and with which support the closure has adjustable engagement, a portion of the closure adapted to enter the said opening from the inside thereof, threads on said portion adapted to engage and disengage the threads in said opening, means for manipulating the closure, said support being spaced from the wall of the container, and an enlarged portion on the closure, said enlarged portion disposed between the support and the adjacent wall of the container.

4. The combination of a container having a threaded opening in the wall thereof, a closure for the opening, said closure disposed within the container, a support for the closure adjacent but spaced from the apertured wall of the container, a threaded connection between the closure and the support, a portion of the closure adapted to enter the said opening, threads on said portion adapted to engage and disengage the threads in said opening, an enlargement on the closure adjacent the said portion, said enlargement being of a size greater than the opening, and means for moving the said portion of the closure into and out of the said opening.

5. The combination of a container having a threaded opening in the wall thereof, a closure for the opening, said closure disposed within the container, a support for the closure adjacent but spaced from the apertured wall of the container, a threaded connection between the closure and the support, a portion of the closure adapted to enter the said opening, threads on said portion adapted to engage and disengage the threads in said opening, an enlargement on the closure adjacent the said portion, said enlargement being a size greater than the opening, and means for moving the said portion of the closure into and out of the said opening, the said enlarged portion adapted to engage the said support for limiting the adjustment of the closure in one direction.

6. The combination of a container having a threaded opening in the wall thereof, a closure for the opening, said closure comprising a body having threaded extremities 5 and an intermediate enlarged portion, a support for the closure, within and spaced from the wall of the container, said support having a threaded opening, said closure disposed within the container, one of the ends 10 of the closure having threaded engagement with the opening in the support, the other end of the closure adapted to engage and disengage the threads in the opening in the said wall and while the closure remains in

engagement with the said support, said enlargement on the closure engaging the inner face of the casing wall and also adapted to engage the support to limit the inward movement of the closure, and means for manipulating the closure. 15

In testimony whereof I have signed my name to this specification, in the presence of two subscribing witnesses, on this 10th day of December A. D. 1914.

ELWOOD C. PHILLIPS.
